UNITED STATES PATENT OFFICE.

CHRISTOPHER C. MUND, OF CINCINNATI, OHIO.

SEPARABLE FASTENING.

No. 882,708.

Specification of Letters Patent. Patented March 24, 1908.

Application filed August 19, 1907. Serial No. 389,119.

To all whom it may concern:

Be it known that I, CHRISTOPHER C. MUND, a citizen of the United States, residing at Cincinnati, in the county of Hamilton and 5 State of Ohio, have invented certain new and useful Improvements in Separable Fastenings, of which the following is a specification.

My invention relates to improvements in garment clasps. One of its objects is to provide a clasp particularly adapted to unite the meeting edges of skirt plackets, wrappers, shirt waists, etc., which will hold the meeting edges of the garment in the desired position.

Another object is to provide such an article 15 in which the members can be easily and conveniently united and disengaged when desired, and which are prevented from becoming accidentally disengaged.

Another object is to provide a clasp for 20 the purpose mentioned adapted in form so that the clasp members may be serially secured to tapes in the process of manufacture, and the tapes stitched or otherwise secured to the garment.

Another object is to provide such an article, 25 which is capable of attachment to tapes, or to be secured directly to the garment as desired.

Another object is to provide an article having the desired characteristics, and which is also capable of being quickly, conveniently accurately and economically manufactured.

It further consists in certain details of form, combination and arrangement, all of 35 which will be more fully set forth in the description of the accompanying drawings, in which;

Figure 1 is a top plan view of the female clasp member. Fig. 2 is a bottom plan view 40 of the male clasp member. Fig. 3 is a central section through the united clasp members and garment. Fig. 4 is a perspective view of the member Fig. 2. Fig. 5 is a plan view of the blank from which the member Fig. 2 is 45 to be formed. Fig. 6 is a central horizontal section through the blank Fig. 5. Fig. 7 is a plan view of the blank for the female clasp member, showing a modification. Fig. 8 is a view similar to Fig. 5 showing a modification. Fig. 9 is a side elevation of Fig. 8. Fig. 10 is a view similar to Fig. 1 showing a modification. Fig. 11 is a section on line $z z$ of Fig. 50 10. Fig. 12 is a view similar to Fig. 2 showing a modification. Fig. 13 is a section on line $x x$ of Fig. 12. Fig. 14 is a central section

through the united clasp members showing a modification of the form shown in Fig. 3. Fig. 15 is a top plan view of a modification of the female clasp member. Fig. 16 is a section on line $v v$ of Fig. 15. Fig. 17 is a plan 60 view of a section of tape with a series of female clasp members attached thereto. Fig. 18 is a plan view of a section of tape with a series of male clasp members attached thereto.

In the accompanying drawings A represents the female clasp member, which in the preferred form is provided with a tubular projection or eyelet a by which it may be firmly and readily attached to a tape B, or if desired directly to the garment. The face or 65 base a' of member A is preferably of triangular outline and sufficient area to retain the member in line with the face of the garment to which it is attached, thus assisting in coupling the members and holding the meeting 70 edges of the garment in line with and overlapping each other, producing the desired 75 neat appearance.

a^2 represent inturned preferably converging ribs forming a shoe or channel a^3 to receive and lock the male clasp member.

C represents the male clasp member, which preferably as shown comprises a piece of material bent upon itself to form a shoe or base c of sufficient area to retain the member 85 C in line with the face of a garment, a tubular projection or eyelet c' which serves to firmly attach it to the tape B' or to the garment directly, and a hook or tongue c^2 overhanging the shoe c and preferably having converging edges c^3 90 to correspond with the converging channel a^3 . The shoe or base c and the tongue or hook c^2 are joined by a free, terminal, preferably curved section or neck c^4 . This free terminal neck serves as a feeler by which the user, 95 by sense of touch, may therewith feel about until the narrow neck has entered into the wider portion of the space between the converging ribs a^2 of the shoe c . This may be accomplished with great facility since the 100 narrow neck c^4 is free of the fabric so that it may be manipulated with great freedom until the proper entrance is found, which may be accomplished with much more facility and ease by reason of this free terminal 105 neck. A hemispherical projection c^5 on the tongue frictionally engages the face of member A during the act of engaging and disengaging the clasp members, and serves together with the resilience of the other engag- 110

ing parts of the respective members to prevent the clasp becoming accidentally disengaged without exerting sufficient pressure to prevent the members being readily disengaged when desired. When the members are fully engaged the projection c^5 enters the recess a^4 formed by the eyelet a , thereby serving to lock the two clasp members together, with the converging edges of the tongue in loose contact with the converging channel a^3 , which prevents any but slight pivotal movement of the clasp members relative to each other, and holds the garment in the desired position.

15 The connection of the tongue and the shoe at the forward narrow end of the male member of the device by a neck which constitutes a free terminal feeler not only insures the tongue entering into engagement with the 20 female member of the device even should the free end of the tongue become accidentally bent down in contact with the shoe, but, as before explained, facilitates, by the sense of touch of feeling, the engagement of the two 25 members of the attaching clasp.

In the modification illustrated in Figs. 7, 8, 9, and 14, the clasp members $A' C'$ in place of being secured to the tape or garment by eyelets, are provided respectively with projections or prongs a^5 and c^6 , which are stamped integral with the members $A' C'$ and bent at right angles thereto, so as to be forced through and clenched upon the opposite side of the tape or garment. In the modification 35 Fig. 7 the member A' is provided with a seat a^6 to register with and receive the projection c^5 of the tongue. In the modification Fig. 14 a projection a^8 from the face of member A' engages the rear end of the tongue c^2 to lock 40 the tongue in place.

In the modification shown in Figs. 10 to 13 the respective members $A^3 C^3$ are pierced with eyes $a^7 c^7$ by means of which the members may be sewed to the tape or garment.

45 In the modification Figs. 15, and 16 the inturned ribs a^9 are lifted and formed from a portion of the tubular projection or eyelet a^{10} of the member A^2 , a member such as shown in Fig. 4 being employed therewith. 50 This modification may be attached to the tape as shown in Figs. 17 and 18, and also so as to stand at right angles to that shown in Figs. 17 and 18, while the other modifica-

tions are usually set as shown in Figs. 17 and 18.

55

In the process of manufacture I preferably attach the clasp members respectively at regular intervals to strong tapes B, B' . In applying the clasps to the garment, sections of the tapes of the desired length are sewed, 60 preferably by machine to the meeting edges of the garment by lines of stitches b, b' .

Having described my invention, what I claim is:

1. In an article of the character indicated 65 a member having means for attaching its base to the garment, and upwardly and inwardly turned ribs; a member bent upon itself to constitute a shoe having means for attaching it to the garment and a tongue 70 overhanging said shoe and connected thereto by a neck, said tongue being adapted to engage beneath the inturned ribs of said first named member, and means for frictionally locking the members against accidental disengagement.

2. In an article of the character indicated, 80 a member comprising a base having a tubular projection upon one side to attach said base to a garment, and converging ways projecting up from the opposite side of said base; and a second engaging member bent upon itself to constitute a shoe and a tongue united by a narrow neck adapted to pass between the converging ways of said first 85 member, the base of said second member having a tubular projection to attach said member to a garment.

3. In an article of the character indicated, 90 a member having means for attaching its base to a garment, said member being provided with converging ways; a member comprising a shoe having means for attaching to the garment, an overhanging tongue having converging edges to engage with the converging ways of said first named member 95 and a narrow, free, terminal neck connecting said tongue and shoe, and being of a width to pass between said ways and to guide the tongue into engagement therewith.

In testimony whereof I have affixed my signature in presence of two witnesses.

CHRISTOPHER C. MUND.
